CLAIM

The ornamental design for a brochure stand, as shown and described.

DESCRIPTION

FIG. 1 is a top, front perspective view of a brochure stand; FIG. 2 is a front elevation view of FIG. 1; FIG. 3 is a right side elevation view of FIG. 1; FIG. 4 is a left side elevation view of FIG. 1; and, FIG. 5 is a top plan view of FIG. 1.

The broken lines showing parts of the brochure stand are included for the purpose of illustrating portions that form no part of the claimed design.
